Specification of Letters Patent. Patented Sept. 23, 1919.

Application filed December 14, 1916. Serial No. 137,033.

To all whom it may concern:

Be it known that I, GEORGE E. WHITNEY, a citizen of the United States, and a resident of Bridgeport, in the county of Fairfield and State of Connecticut, have invented an Improvement in Presses, of which the following description, in connection with the accompanying drawings, is a specification, like characters on the drawings representing like parts.

This invention pertains to improvements in presses and more particularly, though not exclusively, to improvements in presses adapted for applying great pressure to plas- 15 tics confined in a mold, which is automatically filled, covered and emptied by automatic mechanism, coöperating with the compressive instrumentalities.

Among the objects of my invention are to 20 provide a molding press capable of applying high pressure at high speed without the frequent interruptions caused by wear, breakage, and the like, which usually attend the operation of this type of press.

25 Referring to the drawings, which show a preferred construction of one illustrative embodiment of my invention,—

Figure 1 is a side elevation partly in section, showing a preferred embodiment of my 30 invention;

Fig. 2 is a plan view thereof;

Fig. 3 is an end elevation taken from the right of Fig. 1;

Figs. 4 and 5 show the details of the cam 35 mechanism of the press.

The press shown in the drawings is peculiarly well adapted for use in the manufacture of asphalt blocks for paving purposes, which blocks preferably receive a 40 pressure of about 200 tons on a relatively small surface, such as a 60 inch surface of the usual asphalt paving block.

The material prior to compression is 45 granular in form, being composed of a thor- oughly mixed aggregate, comprising heated crushed stone, pulverized stone and a bituminous binding agent. This mixture is fed to the press in granular form at about 290° F., and the compression obtained by 50 the 200 tons of pressure is about 33 $\frac{1}{3}$ per cent., 4 $\frac{1}{2}$ inches of uncompressed material being compressible to form a block three inches in thickness.

The instrumentalities which coöperate to 55 form a press of this type comprise pressure

applying instrumentalities and material handling instrumentalities for feeding material to and from the mold, in which the pressure is applied by the pressure applying instrumentalities.

In the embodiment of my invention, shown in the drawings, I preferably provide compressing instrumentalities including a mold plunger 10, adapted to rectilinearly reciprocate in a mold 11 and to receive pressure from toggle elements 12 and 13. The straightening of the toggle to produce compressive movement of the mold plunger 10 may be actuated in any suitable way, but I prefer to supply a lever arm 14, which may 70 be and preferably is unitary with, or rigidly attached to, the lower toggle element 13, which lever arm 14 is preferably rocked by pressure fluid means typified in the present embodiment of my invention by the 75 steam cylinder 15.

The steam cylinder 15 may be carried by an extension 16 from the bed plate 17 of the press. Within the steam cylinder 15, I preferably provide a reciprocable piston 18 80 having two piston rods 19, extending through the stuffing boxes 20 in the cylinder head 21. Connected to the outer ends of the pistons 19, I may and preferably do provide a cross head 22, which may be and preferably is connected to the lever element 14 at each end by connecting rods 23. Thus rectilinear to and fro movement of the piston 18 in the cylinder 15 imparts rocking movement to the lever element 14, which alternately straightens and bends the toggle 85 formed by the toggle elements 12 and 13, thus imparting compressive and retractive movement to the mold plunger 10.

It will be noted that the application of 90 the predetermined steam pressure to the bottom of the piston 18, will exert a predetermined upward pressure on the outer end of the lever element 14. The amount of pressure imparted to the mold plunger 10 by the toggles 12-13, is not, however, of a fixed or a predetermined quantity, but will 95 vary with the point at which resistance to upward compressive movement of the mold plunger 10 is encountered. This point is 100 likely to vary because of variations in the amount or in the consistency of the material in the mold. Thus if the ultimate compression of the material in the mold be reached 105 after 1 $\frac{1}{4}$ inches of movement of the mold 110

plunger 10, a materially lower potential pressure would be imparted by the mold plunger 10 than if the point of ultimate compression be reached after the mold 5 plunger 10 had completed 1½ inches of compressive movement. This difference in pressure arises, of course, from the different resolutions of forces provided by the toggle 12—13 at different points of relative angularity.

The before described pressure mechanism constitutes one form of variable pressure applying mechanism. Such mechanisms are usually actuated by positive mechanical 15 means, such as a cam acting on a roller mounted on the toggle adjacent the joint thereof. The usual cam and roller construction is objectionable for several reasons, the most important of which are (1) 20 that the rotative power imparted to the cam is necessarily very great and is available to produce breakage in the event of interference or stoppage of any of the coöperating elements of the press and (2) that the friction in the bearing of the roller and between the cam and roller cause heating and excessive wear. The bearings of the toggle itself can, however, be of sufficient size to prevent heating or undue wear. The sliding 25 movement between the various toggle elements is intermittent and of comparatively limited extent.

Thus my invention enables me to avail myself of the simplicity and durability of the 30 toggle while eliminating the usual defects of such mechanism. In practice I prefer to provide sufficient steam pressure to assure a full stroke of the piston 18 in its cylinder 15, thereby imparting a fixed amount 35 of travel to the mold plunger 10. To compensate for variance in the amount of material in the mold and the point at which ultimate compression of the compressed material is reached, I preferably provide 40 coöperating yielding pressure limiting means, which prevents breakage of the parts and limits the pressure applied to the compressed material independently of the pressure fluid actuation of the toggle.

50 In compressing asphaltic and other plastic materials, the resistance to compression is relatively slight at the beginning of the compression, but increases progressively as the material is compressed. It has been the practice in pressure fluid actuated presses to conserve the pressure fluid supply by applying a plurality of compressions increasing in potential pressure. This necessarily complicates the structure. By the use of 55 the pressure fluid means in combination with pressure multiplying means providing an increasing potential multiplication as compression proceeds, I am enabled to more nearly approach at each portion of the compression that potential pressure necessary

to effect compression. This results in a great saving of the pressure fluid and also in a more evenly applied compressive movement of the mold plunger.

I will now describe the molding instrumentalities and will show in what way I have provided in connection with the molding instrumentalities, a preferred construction of yielding pressure determining means, for overcoming the disadvantages attending the variable potential pressures, applied by the compressive instrumentalities. I preferably provide, as shown, two columns 30—30 bolted at their lower ends to the bed plate 17 and arranged one on each side 70 of the lever arm 14. I also preferably provide two supports 31—31 bolted to the opposite side of the bed plate 17 and provided at their upper ends with a bearing 32 adapted to carry a pressure receiving fulcrum or 75 shaft 33. The mold 11 is contained in the mold block 34, which is carried by the pressure receiving bulk-head 35, which is fulcrumed on the axis or shaft 33 and is free 80 to rock about said axis, when a predetermined limit of pressure has been applied to the contents of the mold. The bulk-head 35 is preferably made in two parts, as 85 is best shown in Fig. 3, and carries the mold block 34 and also a rectilinearly reciprocating element 39, having the pressure block 36 and the neck or conduit 37 provided with a hopper 38. The reciprocating element 39, 90 carrying the pressure block and the mold filling neck 37, may be conveniently described as the sliding head 39.

The bulk-head 35 constitutes one form of yielding abutment. Presses having yielding abutments have heretofore been designed with a shiftable mold, which oscillates or 95 rectilinearly reciprocates, relative to the pressure block or molded cover. The shiftable mold and cover which must be oscillated or reciprocated with it are necessarily much heavier than the rectilinearly reciprocable sliding head of the type herein disclosed, thus constituting a speed restrictive element. Another advantage of the disclosed construction is that the mold, sliding head and bulk-head necessarily all yield together when the maximum pressure is 100 reached, thus avoiding separation of the mold from its mold cover, which produces a "fin" or roughness on the upper corners of the compressed block.

To reciprocate the sliding head automatically to fill the mold, cover the mold, uncover the mold and carry away the completed block, I may and preferably do provide a single cycle timing shaft 40, which 105 may be carried in brackets 41—41 on the frames 31—31, and which is preferably provided with a main cam 42 and auxiliary cams 42^a—42^a, adapted to oscillate a sliding head lever 43, which is fulcrumed at its 110 115 120 125 130

lower end in a bearing 44 and which is connected at its upper end to the sliding head by a connecting rod 45. The cams 42, 42^a, 42^b are preferably inverse so that the same 5 distance is constantly maintained between the oppositely effective coöperating cam rollers. To impart oscillatory movement to the sliding head lever 43 by the cams 42, 42^a, 42^b, I preferably provide a roller 46 10 carried by the lever 43, and rollers 47-47 carried by springs 48-48. The roller 46 bears against the main cam 42, while the rollers 47-47 bear against the auxiliary cams 42^a-42^b. The springs 48-48 preferably exert tension to move the rollers 47-47 toward the roller 46. Thus the contact of all three rollers with the main cam 42 and on the auxiliary cams 42^a-42^b, is at 15 all times insured, preventing lost motion and breakage, which usually attend the use 20 of race cams or inverse oppositely effective cams. To increase or decrease the tension on the springs 48-48, I have mounted them on rocker arms 49-49, to which they are pivoted at 50-50, and I have provided set screws 51-51, adapted when screwed in to increase the tension on the springs 48, and when slackened off to decrease such tension. 25 To prevent the springs 48-48 from swinging bodily about the point at which the rocker arms 49-49 are pivoted to the lever 43, thus permitting the rollers 47-47 to get out of proper relation to the coöperating cams 42^a-42^b, I have provided pivoted supports 52-52, adapted to hold the rollers 47-47, and springs 48-48 in their proper operative position, while permitting oscillation of the lever 43.

The springs 48-48 constitute a preferred 40 construction of means for yieldingly maintaining contact between the rollers and the inverse cams 42 and 42^a. This is believed to be broadly new, as applied to producing relative reciprocation of the mold and mold 45 cover of a molding press. The main cam 42 comprises three concentric arcuate portions of different radii connected by suitably inclined portions. These three arcuate portions index the three positions of the 50 sliding head, the arcuate portion having the longest radius being in contact with the roller 46, when the sliding head is in its extreme right hand position with the mold 55 uncovered; the intermediate arcuate portion of the cam 42 being in contact with the roller 46, when the sliding head is in its intermediate position, as shown in the drawing, in which position pressure is applied to the contents of the mold; and the arcuate 60 portion of the cam 40 having the shortest radius, being in contact with the roller 46, when the sliding head is in its extreme forward position with the neck or conduit 47 in register with the mold 11. The cam 42 65 actuates the movement of the sliding head in

the right hand direction, as shown in Fig. 1, including the movement from the filling position to compressing position, and the movement from the compressing position to the mold emptying position, in which the 70 sliding head uncovers the top of the mold, while the contents thereof are ejected by a mechanism to be hereinafter described. The main cam 42 is inverse to the auxiliary cams 42^a-42^b, the distance between the points of 75 contact of the roller 46, and the points of contact of the rollers 47 being constant. The cams 42^a-42^b move the sliding head through its longest movement from the mold emptying position to the mold fill- 80 position, this being caused by the oscillation of the lever 43 from right to left.

To empty the mold when uncovered, independent movement can be given to the mold plunger 10 by ejecting mechanism, 85 which may and preferably does include an ejecting lever 60 fulcrumed at 61 on the frames 31, and having a roller 62 contacting with an ejecting cam 63 on the timing shaft 40. On the opposite end of the lever 60, 90 I preferably provide a roller 64 contacting with a shoe 65, carried by mold plunger guiding levers 66-66, which are fulcrumed at 67-67 to brackets 68-68, carried by the bulk-head 35. The mold plunger guiding 95 levers 66-66 are fulcrumed at 69 to the mold plunger 10 and in coöperation with the ejecting lever 60 and feed regulating means, hereinafter described, prevent the mold plunger from ever dropping entirely 100 out of the mold. Keyed to the shaft 61, which is also the fulcrum of the ejecting lever 60, I preferably provide a feed regulating lever 70, which is connected to a feed rod 71, having a feed nut supported 105 by a feed regulating screw 73, which is rotatable in the feed regulating nut 74 by any suitable means typified by the feed regulating arms 75. A manual rotation of the feed regulating arms 75 produces either upward 110 or downward movement of the feed regulating screw 73 relative to the fixed feed regulating nut 74 and thus raises or depresses the rod 71, which through the lever 70, shaft 61, lever 60 and guide lever 66, regulates the drop of the mold plunger or the receiving capacity of the mold when in filling position.

The relative timing of the compressive instrumentalities and molding instrumentalities, before described, is assured by mounting the valve controlling cam 80 on the timing shaft 40. The cam 80 through levers 81 and 82 fulcrumed at 83 and 84, actuates reciprocation of the valve control rod 85, thereby causing rocking motion of the valve rocker shaft 86, on which is mounted a lever 87 adapted to impart reciprocatory motion to a slide valve 88 in the steam chest 89 of the steam cylinder 15. When the valve 130

controlling lever 85 is rocked to the left, the steam is admitted from the valve chest 89, through the admission port 91^a, thereby moving the piston 18 upwardly. At the same time the slide valve 88 has connected the exhaust port 91 with the exhaust 92, thereby permitting the escape of the steam from the upper part of the cylinder, as the piston 18 moves upwardly. In the event 10 that no material is contained in the mold and no substantial resistance is opposed to the mold plunger, the piston 18 may move with great velocity and tend to strike the cylinder head 21. To prevent this a steam cushion is formed in advance of the piston 18 as soon as the latter has passed the exhaust port 91. This cushion is formed because the exhaust port 91 will have been covered by the piston 18, while the admission port 93 is covered by the slide valve 88.

Conversely, the movement of the valve controlling element to the right produces downward movement of the slide valve 88, thereby opening the admission port 93 to the steam chest, while opening the exhaust port 90 to the exhaust 92 and covering the port 91^a, to provide a fluid pressure buffer between the piston 18 and the bottom of the cylinder 15.

30 I preferably interpose in the return admission port 93 the valve 93^a, whereby the rate of admission of pressure fluid to the top of the piston 18 may be varied, thus preventing the admission of too great a 35 volume of steam to the top of the piston 18 for the return stroke of said piston which might cause damage to the machine.

I preferably provide the toggle members 12 and 13 with projections 200—201, 202—40 203, 204—205 so proportioned and placed relative to each other that when the piston 18 is at the bottom of its stroke, these projections butt together, thereby lifting each bearing of the toggle slightly from its corresponding seat, thereby permitting efficient distribution of the oil to the toggle bearings.

While the before described fluid pressure buffer mechanism is very efficient, I 50 preferably provide a form of floating valve so that the movement of the slide valve 88 is controlled, not only by the rocking of the valve rocker shaft 86, but also indirectly by the pressure fluid actuated movement of 55 the piston 18. To this end I preferably provide an arm 100 on the cross head 22, to which arm is connected one end of a link 101, the other end of said link 101 being connected to a floating valve lever 102, carrying an eccentric 103, about which is provided an eccentric strap 104 connected to the slide valve stem 105. The valve lever 87 is connected to the eccentric 103 and forms the fulcrum thereof.

The operation of the valve actuating and 65 the floating valve mechanism is as follows:

When the lever 85 is moved to the left, it rocks the levers 86 and 87, which form a bell-crank, thus raising the slide valve 85. As steam is admitted to force the piston 18 upward, the floating valve lever 102 is raised at one end by the link 101, rocking the lever about the connection at 87 as a fulcrum, thereby providing downward movement to the eccentric 103 and imparting downward movement to the slide valve 88. Thus the effective travel of the slide valve 88 depends on two factors: first, cam actuated movement through the lever 85 and second, piston actuated movement through the floating 70 valve lever 102. If too little resistance is opposed to upward movement of the piston 18, the floating valve will cut off the supply of steam to the lower side of the piston 18 and may even admit steam to the upper side 75 of said piston and check the speed at which the piston moves on its upward stroke. The specific floating valve lever mechanism described is peculiarly advantageous because 80 of its compact form and its simplicity.

One of the difficulties incidental to the maintenance of a press of this character is caused by the leakage of material from the mold 11 about the mold plunger 10, as the material falls directly on to the mechanical pressure mechanism underneath, as herein typified by the toggles 12—13. I prevent this material which is gritty in its nature, from getting into the joints of the toggle, by providing the upper end of the toggle 95 element 12 with a shield 110, fastened to the toggle bearing cap 11, which is carried by the mold plunger carrying toggle shaft 112. The toggle cap 111, the mold plunger carrying shaft 112 and the guard or apron 100 110, are all reciprocable with the mold plunger 10 during both its compressive and 105 ejecting movement. During the ejecting movement of the mold plunger 10, the toggle portion 12 is held in proper relation to the mold plunger carrying shaft 112 by an 110 elongated portion of the guard 110 constituting the guiding apron 110^a, which serves not only as a protection for the upper toggle bearing, but also as a guide. The 115 knuckle bearing 113 of the toggle is similarly protected by guards 114, 115, 116, while the lower toggle bearing 117 is protected by guards 118—119—120. The ends of the toggle bearings 112—113 and 117, are 120 protected by similar sheet metal plates, which serve not only to prevent the entrance of dust but to retain the oil in these bearings.

I will now describe the typical operation 125 of the whole press. Let us assume that the time shaft 40 is turned in such position that the neck 37 is registered with mold 11. At

this point the mold plunger 10 is in its lowest position as determined by the adjusting movement of the feed regulating screw 73; thus the material actuated by gravity will 5 slide down the neck 37 filling the mold 11. The sliding head is then moved to the right by operation of the main cam 42 until the pressure block 36 covers the mold, as shown in Fig. 1. The valve cam 80 then moves 10 the valve rod 85, rocking the bell-crank 86—87, thereby imparting movement to the slide valve 88, thus admitting steam below the piston 18. As the piston 18 responds to the pressure fluid, the arm 100 and the link 101 15 will rock the floating valve lever 102 about its connection with the lever 87, thereby tending to regulate the speed and movement of the piston 18 if too little resistance is encountered. When the piston 18 closes 20 the port 91, it will encounter the pressure fluid cushion caused by closure of the port 93. The before described piston travel will raise the toggle lever element 14, thereby straightening the toggle 12—13 and imparting 25 pressure to the mold plunger 10.

In the event that there is more material in the mold than can be compressed by the movement imparted to the mold plunger 10, the whole structure including the mold 30 block 34, the bulk heads 35 and the sliding head will be rocked about the axis of the shaft 33. To predetermine the pressure which the bulk heads 35 and associated parts shall withstand prior to yielding, I 35 provide any suitable form of pressure determining means, herein shown as projections 130 attached to the bulk heads 35 at the outer end, to which projections I may connect weights or a steam cylinder and 40 piston, thereby affording as desired, either gravity actuated pressure determining means or pressure fluid actuated pressure determining means. The normal position of the bulk-heads 35 and associated parts 45 are determined by projections 131 on the columns 30, on which the bulk-head 35 and associated parts rest, except during the periods when pressure is applied.

After a suitable period, during which the 50 material in the mold is held under compression, further rotation of the timing shaft 40 causes the valve cam 80 to move the valve control rod 85 to the right, thereby moving the slide valve 88 downwardly and admitting 55 pressure fluid to the top of the piston 18, through the admission port 93, thereby imparting downward movement to the piston and to the mold plunger 10. After the mold plunger 10 has dropped sufficiently to 60 relieve the pressure of the material in the mold, the sliding head is again moved to the right in such position that the top of the mold 11 is uncovered. This movement to the right is actuated by the main cam 42 65 acting on the roller 46 of the reciprocating

sliding head 43. The mold now being uncovered, the ejecting cam 63 rocks the lever 60, thereby elevating the mold plunger 10 which is guided by the mold plunger guide lever 66, thereby ejecting the completed 70 block from the mold 11. During this ejecting movement the upper bearing 11 of the upper toggle 12 is lifted away from the main portion of the toggle 12, the toggle 12 being supported by the apron 110^a. As soon 75 as the mold plunger 10 has been elevated to such position that it is flush with the upper face of the mold block 34, the sliding head is moved to its extreme left hand position by operation of the main cams 42^a—42^a 80 on the rollers 47. During such movement the compressed block is pushed to the left from the top of the plunger 10 and at the end of such movement the neck 37 again registers with the mold 11. The mold 85 plunger 10 is now permitted to drop by the ejecting cam 63, and the column of material passing down the neck fills the mold 11, thereby completing one cycle of operation 90 of the entire press.

Power may be imparted to the timing shaft 40 from any suitable source, preferably through gearing typified by a pulley 140, pinion 141 and timing shaft gear 142.

The pressure-receiving abutment may be 95 held down in any suitable way, preferably by means adapted to exert a constant amount of pressure thereon. This means may take the form of a weight, and this weight may conveniently take the form of 100 a pipe, a column of water or other liquid therein and, if desired, a tank carried thereby so that the amount of pressure available may be varied in accordance with the amount of water pumped into or out of the 105 system. In Fig. 6 I have shown such a pipe, column and tank extending upwardly through several floors of a building, the pipe being slidably guided through the floors and roof. Fig. 7 shows a detail of 110 the mechanism shown in Fig. 6.

While the drawings show and while I have described one specific embodiment of my invention, it will be understood that changes involving alteration, substitution, 115 omission, reversal and re-arrangement of parts and even changes in mode of operation may be made without departing from the scope of my invention. My invention and what I desire by Letters Patent to procure is best described in the following claims:

1. A block molding press comprising, in combination, a mold in which the blocks are compressed, a mold plunger reciprocable in 125 said mold, a toggle for imparting compressive movement to said mold plunger, lever means rigidly connected to that member of the toggle farthest removed from said mold plunger, pressure fluid means acting on said 130

- lever for straightening said toggle to actuate compressive movement thereof, and pressure-determining means for limiting the pressure applied to the blocks in said mold.
5. A molding press comprising, in combination, a mold, a plunger vertically reciprocable therein, a vertically arranged toggle, a lever rigidly connected to the lower portion of said toggle, a cylinder having a vertically arranged axis for swinging said lever to straighten said toggle, ejecting means for imparting mold-emptying movement to said mold plunger independent of said toggle, and a shaft arranged on the 10 opposite side of said toggle from said cylinder for timing the periods of operation of said toggle and of said ejecting means.
3. A molding press comprising, in combination, a yielding pressure-receiving abutment, a fulcrum for said abutment, and means operatively connected to said abutment for exerting downward pressure to resist pressure-actuated yielding movement thereof, said means providing for an upward 25 strain on said fulcrum.
4. A molding press comprising, in combination, a yielding pressure-receiving abutment, a mold and a mold cover reciprocable in and yielding with said pressure-receiving 30 abutment.
5. A molding press comprising in combination a mold plunger, a toggle for imparting compressive movement thereto, lever means rigidly connected to operate said 35 toggle, a pressure fluid cylinder, its piston, a crosshead for said piston and a plurality of connecting rods for transmitting pressure fluid actuated movement of said cross-head to said lever means to actuate compressive 40 movement of said toggle.
6. A molding press comprising in combination a mold plunger; a pressure fluid actuator for imparting compressive movement to said mold plunger; and a yielding abutment opposed to said mold plunger.
7. A molding press comprising in combination a yieldingly actuated, normally fixed throw mold plunger; a mold; a reciprocable closure for said mold; and a yielding support for said mold and said mold 50 closure.
8. A molding press comprising in combination a normally fixed throw mold plunger; a yielding abutment; a mold block and a sliding head; said mold block and said sliding head being carried by said yielding abutment.
9. A molding press comprising in combination a mold plunger; a mold block; a 60 sliding head and an abutment, said abutment being pivotally mounted for yielding movement at a predetermined pressure and carrying said mold block and said sliding head.
- 65 10. A molding press comprising in combination a mold plunger; a mold containing element; a closure for the mold; operating means for relatively shifting said mold containing element and said closure; and an abutment mounted for yielding movement 70 at a predetermined pressure and carrying said mold containing element and the shiftable element.
11. A molding press comprising in combination a mold, a plunger, a timing shaft, 75 a pressure fluid cylinder for operating the plunger, its piston, a valve cam on said timing shaft for actuating said valve, an eccentric operatively interposed between said cam and said valve, and means connected to said piston for turning said eccentric to modify the movement imparted to said valve by said valve cam.
12. A block molding press comprising, in combination, a mold in which the blocks are compressed, a mold plunger reciprocable in said mold, a toggle for imparting compressive movement to said mold plunger, pressure fluid means for straightening said toggle to actuate compressive movement 80 thereof, and pressure-determining means for limiting the pressure applied to the blocks in said mold.
13. A molding press comprising in combination a mold plunger; its mold; ejecting 85 means and a pivoted guide for said mold plunger effective to maintain said mold plunger in substantial alinement with said mold during its compressive and ejecting movements.
14. A molding press comprising in combination a mold; its mold cover and operating means for producing relative movement of said mold and mold cover; said operating means including inverse cams; rollers for 90 said cams; spring means connecting said rollers, and means for increasing and decreasing the pressure of said rollers on said cams by increasing or decreasing the pressure of said spring means.
15. In a molding press having a mold and mold cover; operating means for changing the relative position of said mold and mold cover; said operating means including a lever connected to the moving part; a rotary cam shaft and inverse cams mounted thereon; a plurality of rollers coöperating with said cams and operatively connected to said lever; one of said rollers being on the same side of said cam shaft as said lever; the other roller being on the opposite side of said cam shaft.
16. In a molding press having a mold and mold cover; operating means for changing the relative position of said mold and mold 105 cover; said operating means including a lever connected to the moving part, a rotary cam shaft and inverse cams mounted thereon; a plurality of rollers coöperating with said cams and operatively connected to said 110
10. A molding press comprising in combination a mold plunger; a mold containing element; a closure for the mold; operating means for relatively shifting said mold containing element and said closure; and an abutment mounted for yielding movement 115 at a predetermined pressure and carrying said mold containing element and the shiftable element.
11. A molding press comprising in combination a mold, a plunger, a timing shaft, 120 a pressure fluid cylinder for operating the plunger, its piston, a valve cam on said timing shaft for actuating said valve, an eccentric operatively interposed between said cam and said valve, and means connected to said piston for turning said eccentric to modify the movement imparted to said valve by said valve cam.
12. A block molding press comprising, in combination, a mold in which the blocks are compressed, a mold plunger reciprocable in said mold, a toggle for imparting compressive movement to said mold plunger, pressure fluid means for straightening said toggle to actuate compressive movement 125 thereof, and pressure-determining means for limiting the pressure applied to the blocks in said mold.
13. A molding press comprising in combination a mold plunger; its mold; ejecting 130 means and a pivoted guide for said mold plunger effective to maintain said mold plunger in substantial alinement with said mold during its compressive and ejecting movements.

lever; one of said rollers being on the same side of said cam shaft as said lever; the other roller being on the opposite side of said cam shaft; and a support for the latter roller.

17. A molding press comprising in combination a mold plunger; a toggle for imparting compressive movement to said mold plunger; oil retaining means at the joints of 10 said toggle and heels adjacent the joints of said toggle adapted to cause separation of the elements of the toggle at the joints thereof when said toggle is in flexed position to permit the thorough lubrication of the 15 joints of said toggle.

18. A molding press comprising in combination a mold plunger; a pressure fluid cylinder; a piston in said cylinder, one side of said piston being effective on the admission 20 of steam to effect compressive movement of said mold plunger, and the other side of said piston being effective on the admission of steam to effect return movement of said piston; valve means for controlling 25 the admission and exhaust of pressure fluid from each end of said cylinder; a return pressure fluid admission passage for admitting pressure fluid to the return end of said cylinder; a throttling element in said return

admission passage; and an exhaust passage 30 independent of said return admission passage for permitting unthrottled exhaust of pressure fluid from the return end of said cylinder.

19. A molding press comprising in combination a mold plunger; a yielding abutment opposing said mold plunger; a pivoted support for said yielding abutment; and gravity actuated means projecting beyond the molding portion of the press and providing 40 with said pivoted support, a second-class lever opposing the yielding of said abutment.

20. In a molding press having a mold and mold cover, operating means for changing 45 the relative position of said mold and mold cover; said operating means including a rotary cam shaft and inverse cam means mounted thereon; a plurality of rollers co-operating with said cam means, one on one 50 side of said shaft and the other on the opposite side of said shaft, and resilient means pressing said rollers together and against said cam means.

In testimony whereof, I have signed my 55 name to this specification.

GEORGE E. WHITNEY.
